CHARLES M. STOCKER, OF GEORGETOWN, MASSACHUSETTS.

Letters Patent No. 106,228, dated August 9, 1870.

IMPROVEMENT IN FEEDING DEVICE AND PRESSER-FOOT FOR SEWING-MACHINES.

The Schedule referred to in these Letters Patent and making part of the same

To all persons to whom these presents may come:

Be it known that I, CHARLES M. STOCKER, of Georgetown, of the county of Essex and State of Massachusetts, have made a new and useful Improvement in the Feeder and Presser-Foot of Sewing-Machines; and I do hereby declare the same to be fully described in the following specification and represented in the accompanying drawing, of which—

Figure 1 denotes a front elevation of a presser-foot and a feeder of a sewing-machine, as recessed in accordance with my invention.

Figure 2 is a top view of the feeder, and

Figure 3, a bottom view of the presser-foot.

Figure 4 is a top view of the feeder, as recessed on one side only of the needle-slot.

Figure 5 is an under-side view of the presser-foot, as similarly recessed.

In carrying out my invention I form in the presser-foot a notch or recess, to extend from the needle-slot, laterally, either to one or both of the opposite edges of the foot, and I also form another notch or recess in the feeder in substantially the same manner.

In the drawing—

A denotes the presser-foot, and

B the feeder, *a* denoting the needle-slot in the one, and *b* that in the other.

The recess of one is exhibited at *c*, and that of the other at *d*.

Figs. 2 and 3 represent these recesses as extending entirely across the two articles, while figs. 4 and 5 represent such recesses as opening out of one side only of the needle-slots.

The recess of the feeder is sunk downward from its toothed or notched surface.

The said recesses leave the thread in the material unclamped while the stitch is being formed, and consequently free to be drawn therein, and they also allow such material to be turned in either direction under the presser without requiring for such any stoppage of the machine.

The formation of the notches or recesses in one way only out of the needle-slots of the feeder and

presser-foot will enable the work to be turned only to the right or to the left, according as the notches may be arranged; but by extending the notch or recess entirely across the feeder, and also entirely across the presser-foot, the work can be turned either to the right or to the left without the stitch becoming clamped or pinched, so as to be prevented from being drawn closely into the work.

I am aware that the feeder of a sewing-machine has been grooved, dented, or serrated for the purpose of enabling it to properly act on the work for advancing it or feeding it along, such forming no part of my invention, which involves the employment of notches or recesses, to extend entirely below the teeth or holding-grooves or devices of the upper surface of the feeders.

I would remark that my improvement is designed especially for chain-stitch sewing-machines, in which an awl and a needle are employed, such machines being designed for the sewing of leather. The well-known Whittemore machine, of this nature, is one to the presser-foot and feeder of which the invention is peculiarly appropriate, and on which I have employed it to great advantage.

The recesses of the feeder and the presser-foot are to be so arranged, with reference to the needle, as to receive the stitch while it is being drawn into the work, and also admit of the work being duly clamped by the presser-foot and the feeder at such times as it may be necessary for the awl and the needle to pass into and out of the work.

What I claim as my invention is—

The presser-foot and feeder, provided with the stitch-receiving recesses, arranged with reference to their needle-slots, and so as to extend therefrom laterally out of the feeder and presser-foot, as and for the purpose as hereinbefore explained.

CHAS. M. STOCKER.
